HEAT REFLECTING DEVICE

Sidney Adolph Horstmann, Bath, England

Application November 27, 1931, Serial No. 577,685.
Renewed November 26, 1934. In Great Britain
December 10, 1930

2 Claims. (Cl. 219—34)

This invention relates to a new form of heating apparatus whereby heat from a heating element or elements is distributed by rotating or oscillating reflectors, the motion being imparted to the said reflectors by convection currents of air from the source of heat or by any known mechanical means.

The object of this method of distribution is to sweep any predetermined plane (e. g. a horizontal plane like a floor) or planes with a continuously moving beam or beams of heat, which may be wholly reflected or indirect beams, or preferably a combination of indirect and direct beams.

One way of carrying this invention into effect is to mount three leaf-shaped reflectors angularly equidistant apart on a centre plate and spaced so that the beam of one reflector can be projected between the other two; between these reflectors or leaves and above the reflecting beam three smaller leaves or vanes are mounted and so shaped that they act as impellers to rotate the whole around a centre or bearing mounted in the centre plate. A suitable heating element is mounted more or less central in relation to the reflectors and in a suitable plane in relation to them. A large proportion of the heat of the element is reflected by the reflecting leaves, but convection currents of air are set up to a certain extent which have the effect of rotating the device around a suitable support for the centre or bearing.

For a clearer understanding of this invention reference may be made to the accompanying drawing in which various embodiments are illustrated by way of example only, and wherein like letters indicate corresponding parts in the several views. In said drawing:—

Figure 1 is a side elevation of one form of this invention;

40 Figures 2 and 3 are elevations showing two alternative methods of supporting the bearing of rotor; and

Figure 4 is a diagram of a totally enclosed form hereinafter described.

45 Referring to Figure 1, *a*, *a*, *a* are the reflecting vanes, *b*, *b*, *b* are impeller vanes, and *c* is a suitable centre plate to which all vanes are fixed. A base *g* is provided with an insulator *h* which carries an electrical heating element *e* shown dotted.

50 Above the element may be mounted a deflector plate *f*. A cranked vertical support *d* has a hollow centre to receive a needle point *j* which is fixed in a suitable needle holder bolted to the centre of plate *c*. The aforesaid vertical support is rigidly attached to the base *g* in any suitable

manner. The knob *i* forms the apex to which three bent rods are attached which are fixed to the base *g* and form a protecting cage, the knob *i* forming a convenient means of handling the stove.

5 Figures 2 and 3 show modifications of the apparatus with vanes removed for clearness. In Figure 2 a central vertical support rod passes through the heating element. With this construction the element imparts considerable heat 10 to this vertical rod and in order to prevent destructive heating effects being conducted to the bearing the rod is bent into coils such as *x*, *x*. The coils are preferably of helical formation which do not touch where they cross one another.

15 With this arrangement the vertical support rod *d* is conveniently attached to the insulator *h* and may also pass through the top of base *g* thus forming a convenient means of attaching these two parts. Further modifications shown in Figure 2 are the additions of the bridge piece *k* and the carrying ring *l*. The needle bearing is here enlarged to form a tapered shoulder, and the bridge piece *k* is pierced with a hole of smaller size than the taper on shoulder but a loose fit on 20 the spindle, so that when the device is working no friction results except on the bearing proper. However, when it is desired, the whole apparatus can be carried by the ring *l* because the weight of the base and heating element is taken by the 25 taper shoulder of the spindle jamming in the hole of the bridge piece *k*.

30 The bridge piece *k* is advantageously made quickly detachable from the centre plate *c* so that the bearing or needle point can be quickly removed when worn or damaged. Figure 3 shows another form of heat insulator for the bearing *j*; in this case the spindle *d* is shorter and threaded at the top end to receive a nut. A ring *m* of 35 preferably flat section steel is joined by an insulator *o* to which it may be riveted. In the centre of this insulator *o* is mounted a needle bearing corresponding to that in Figure 2. The ring *m* is conveniently attached to the spindle *g* by a nut of any form which may also serve to 40 secure the deflector plate *f*. With the construction shown in Figures 2 and 3 the protecting cage and knob *i* may be eliminated.

45 The reflectors *a* may be so arranged that they completely or substantially surround the heating element or elements. In this case they could be so shaped in helical or other formation that the inside of one would reflect to the outside of another and from thence to the area to be heated. For example in Figure 4 a series of reflectors *p* 50

of the louvre form (two only of which are shown) surround the heater *e*. The heat rays strike the inner surfaces *r* and are reflected to the adjacent outer surfaces *s* and thence to the surface 5 rounding area to be heated. The reflectors *p* may be solid or hollow. In this case the reflectors may form their own impellers for rotation.

In the accompanying drawing an electrical element has been shown but any other form of heat 10 such as gas, oil or the like may be used.

The bearing on which the vanes rotate may be of any known form. In the forms illustrated a hollowed centre has been provided on the vertical support and a needle mounted in a holder 15 which carries the vanes. The hollowed centre may be filled with thick oil for lubrication.

It should be clearly understood that I do not restrict myself to the construction described and illustrated and that many variations fall within 20 the scope of the invention as defined by the appended claims.

I claim:

1. In a heating apparatus the combination of a

heating element, rotatable impeller and separate heat reflecting members associated in angular relation with said heating element whereby convection currents of air from said heating element impinge against said impeller thereby causing same to rotate and in turn rotate said heat reflecting members.

2. A heating apparatus comprising a heating element, a support extending above said heating element and directly exposed to the heat thereof, a bearing carried by said support, heat reflecting members rotatably mounted on said bearing and disposed to reflect heat laterally from said heating element, and means separate from said members connected therewith and disposed to be rotated by convection currents emanating from the heating element thereby to impart rotation to the reflecting members, said support having a ring-like formation to impede the conduction of heat through the support to the bearing.

SIDNEY ADOLPH HORSTMANN.
